UNITED STATES PATENT OFFICE.

JOHN MEGSON, OF ADAMS, MASSACHUSETTS.

STOP-MOTION FOR LOOMS.

SPECIFICATION forming part of Letters Patent No. 348,761, dated September 7, 1886.

Application filed April 14, 1885. Serial No. 162,256. (No model.)

To all whom it may concern:

Be it known that I, JOHN MEGSON, of Adams, in the county of Berkshire and State of Massachusetts, have invented a new and Improved 5 Stop-Motion for Looms, of which the following is a full, clear, and exact description.

The object of my invention is to provide a new and improved stop-motion for looms, which automatically shifts the belt and stops 10 the loom in case the shuttle fails to leave the box. If the shuttle should fail to leave its box in a single shuttle-loom such as shown in the drawings, while a pattern was being formed by the harness and the loom were allowed to run, both the take-up and pattern-chain would require adjusting, and hence it is 15 very essential that the loom should be stopped at such times to avoid this adjustment. With a loom employing more than one shuttle, if 20 one shuttle should fail to leave its box the first shuttle that moved from the other side of the lay, after the failure of the shuttle to leave the box, would be prevented from entering the box, and consequently would remain between 25 the warp-threads, and when the lay returned on the beat-up the shuttle would cause the warp-threads to break.

The invention consists in numerous parts and details, and combinations of the same, as 30 will be fully described and set forth herein-after.

Reference is to be had to the accompanying drawings, forming part of this specification, in which similar letters of reference indicate 35 corresponding parts in all the figures.

Figure 1 is a front view of the lay of a loom having applied thereto a portion of my improved automatic stop-motion. Fig. 2 is an inside view of the breast-beam, showing applied to the said beam another portion of my improved stop-motion. Fig. 3 is a cross-sectional view of the breast-beam and the lay on the line *x x*, Fig. 2. Fig. 4 is a detail cross-sectional view of the breast-beam on the line 45 *y y*, Fig. 2. Fig. 5 is a plan view of the lay. Fig. 6 is a plan view of the under side of the breast-beam. Fig. 7 is a similar view to Fig. 3, with the lower parts broken off and showing the parts in a different position.

50 The lay *A* is mounted to swing between the side pieces of the base-frame *A'*, in the usual

manner, toward and from the breast-beam, also secured on the base. On the upper part of the lay the shuttle-race *C* is formed, and at the ends thereof are the boxes *C'* for receiving the shuttle *D*, of the usual construction. The front of each box is formed by a curved lever, *E*, pivoted at the outer end of the lay in such a manner as to swing toward and from the back of the lay, the said lever *E* being 60 pushed inward by a spring, *F*, surrounding a pin, *F'*, passing through an arm, *G*, projecting upward from the front of the lay.

In jaws or lugs *H* on the front of the lay the shaft *J* is journaled, the middle of which is 65 supported by a forked piece, *J'*, between the prongs of which a dagger, *K*, projects from the shaft *J*, the free end of the dagger being provided with a downwardly-projecting prong, *K'*, and a top prong, *K''*, as shown in Fig. 3. 70

From the shaft *J* arms *L* project upward, which are provided at their upper ends with heads *L'*, resting against the outer swinging ends of the levers *E* at the ends of the lay. Springs *I* are coiled around the ends of the 75 shaft *J*, each having one end resting against the adjacent arm *L*, and the other end against the under side of the lay-beam and pressing the arms *L* against the levers *E*.

From the under side of the breast-beam *B'* 80 jaws *M'* project downward, and between the lower ends of the same a forked piece, *M*, is pivoted, to the rear part of which a supplementary bunter, *N*, is pivoted. The supplementary bunter is provided with notches or 85 grooves *n*, to receive the lower prong, *K'*, of the dagger *K*, and has its upper end forked to form two prongs, *N'*, having notches *M'* in their front edges at the top, so as to adapt the said prongs to fit against the bottom and rear 90 edges of the usual bunter. The bunter *O* is pivoted to the under side of the breast-beam, and is provided in its front edge with a groove, *O'*, for receiving the upper prong, *K''*, of the dagger *K*. A spiral spring, *P*, secured to the 95 supplementary bunter *N* and to the breast-beam, presses the upper ends of the prongs *N'* of the supplementary bunter upward against the bottom and front edges of the usual bunter, *O*. Prongs *P'*, having their bottom edges 100 beveled or rounded upward, project from the back of the supplementary bunter *N*, and

prongs P^2 , having their top edges beveled downward, project from the jaws M' slightly below the prongs P' . The bunter O rests against the belt-shifting lever Q , which is pressed in the 5 inverse direction of the arrow a' —that is, from the side of the breast-frame—by a suitable spring, Q' . The upper or handle end of the said belt-shifting lever Q passes through a slotted arm, Q^2 , projecting from the end of the 10 breast-beam, and having a notch, Q^3 , for receiving the said lever Q . The said hand-lever Q also passes through a slot in the sliding piece R , arranged to slide in the end of the frame and on the under side of the slotted 15 arm Q^2 , which slide is provided with a button, R' , projecting into its slot. The sliding piece R is also provided with a prong, R^2 , having its end beveled, and forming a pocket for receiving the lever Q . A lever, S , is pivoted at 20 its middle on a hanger, S' , extending downward from the breast-beam, and is provided in one end, which is bent downward rectangularly, with a notch for receiving a pin, T , projecting from the forked piece M , to which 25 the supplementary bunter N , is pivoted. At its opposite end the said lever is provided with a slot, S^2 , into which a pin, T' , passes, which is secured in the inner end of the sliding piece R . The belt-shifting fork is connected by a rod, W , with the lever Q . The other parts of the loom are of usual construction, and are not affected by the arrangement or construction of my improved stop-motion.

The operation is as follows: When the loom 30 is in motion the lever Q is held in the notch Q^3 in the arm Q^2 , and the belts are so adjusted as to drive the loom. The lay swings toward and from the breast-beam. As the lay moves in the direction of the arrow b' , Fig. 3, toward 35 the breast-beam, the lower prong, K' , of the dagger K will pass between the prongs N' of the supplementary bunter N , as clearly shown in Fig. 3. When in this position, the shuttle enters one of the boxes, and in doing so pushes 40 the lever E outward, which, acting upon the head L' of one of the arms L , turns the shaft J , and thereby lowers the dagger, so that as the lay continues to move toward the breast-beam the supplementary bunter N will be 45 depressed by the dagger to such an extent that the dagger will pass between the two bunters to the position shown in Fig. 7 without stopping the loom. After the lay has moved back the spring P returns the supplementary bunter 50 N to its normal position. If, when the parts are in the position shown in Fig. 3, the shuttle should fail to enter the box, the dagger will not be depressed, and as the lay continues to move forward the upper prong, K^2 , of the dagger will strike the ordinary bunter, O , and swing the inner end of the same in the direction of the arrow b' , thereby swinging the outer end in the reverse direction of the 55 said arrow, and causing the same to push the lever Q out of its notch Q^3 , and permitting the spring Q' to throw the said lever Q in the reverse direction of the arrow a' ,

whereby the belt will be shifted and the loom stopped. It is to be understood that the upper prong, K^2 , of the dagger is always in position to strike the ordinary bunter, O , as the lay moves forward when the shuttle is out of the boxes. Should, however, the shuttle fail to leave its box in the forward movement of the lay and before it arrives at the position shown 70 in Fig. 3, the dagger being depressed its lower prong, K' , will strike the supplementary bunter N , which, resting against the ordinary bunter, O , will cause the said bunter O to push the lever Q out of its notch and stop the loom, 75 as above described. The loom will also be stopped by the lower prong, K' , of the dagger striking the supplementary bunter N , should the dagger fall below its normal position by the weakening of the springs I , 80 or for any other cause. The pins $P' P^2$ on the jaws M' , and the supplementary bunter N , respectively, prevent the supplementary bunter from being swung down below the ordinary bunter, O , when the supplementary bunter is struck by the lower prong, 85 K' , of the dagger to stop the loom. At the same time that the lever Q is tripped to stop the loom it pulls the slide R outward with it, so that the outer end of the lever S 90 will be raised and the inner end depressed, which movement will swing the supplementary bunter downward out of the way of the dagger, thereby permitting the lay to be 95 pushed back without removing the shuttle from the box. When the lever Q is moved 100 in the direction of the arrow a' into the notch Q^3 to shift the belt and start the loom, the said lever strikes the button R' in the sliding frame or piece R and moves the same in the direction of the arrow a' , and causes it to lower the outer end of the lever S , whereby the inner end of said lever is raised so as to permit the spring P to pull the supplementary bunter N up against the ordinary bunter, O .

Having thus fully described my invention, I claim as new and desire to secure by Letters Patent—

1. The combination, with the breast-beam, the usual bunter thereon, the lay, and shipper-lever, of a supplementary bunter on the breast-beam, a forked dagger on the lay, and means for raising and lowering the dagger to cause its prongs to strike one or the other of the bunters to operate the shipper-lever to 115 stop the loom when the shuttle is out of the box or should it fail to enter the same at the proper time, substantially as herein shown and described.

2. The combination, with the breast-beam, 120 the usual bunter thereon, the lay, and shipper-lever, of a supplementary bunter on the breast-beam, a shaft journaled on the lay, a forked dagger on the shaft, levers on the ends of the shaft, and levers on the lay and engaging the levers on the shaft, substantially as 125 herein shown and described.

3. The combination, with the breast-beam, 130 lay, and shipper-lever, of an ordinary bunter

pivoted to the under side of the breast-beam, a supplementary bunter hung on jaws depending from the under side of the breast-beam and having its upper end resting against the ordinary bunter, a shaft journaled on the lay, a dagger at the center of the shaft, upwardly-projecting levers on the ends of the shaft, and levers pivoted to the lay and engaging the levers on the shaft, substantially as herein shown and described.

4. The combination, with a breast-beam and a lay, of a shaft, a dagger, the levers E L, the bunter O on the breast-beam, the hangers M', the forked piece M, the supplementary bunter N, the spring P, the lever S, connected with the said forked piece M, the sliding frame R, the belt-shifting lever Q, and a projection on the sliding frame R for acting on the said belt-shifting rod or lever Q, substantially as herein shown and described.

5. The combination, with a breast-beam and

a lay, of a shaft, a dagger thereon, the levers E L, the bunter O on the breast-beam, the hangers M', the forked piece M, the supplementary bunter N, the spring P, the lever S, 25 the slide R, connected with the same and having the button R', the slotted guide-arm Q², having a notch, Q³, and the belt-shifting lever Q, substantially as herein shown and described.

6. The combination, with the breast-beam 30 and lay, of jaws M', projecting down from the breast-beam, the forked piece M, pivoted to the same, the bunter O, the supplementary bunter N, pivoted to the forked piece M, and the pins P' and P² on the jaws M', and the supplementary bunter N, substantially as herein shown and described. 35
